CLAIM

The ornamental design for a coordinate input instrument, as shown and described.

DESCRIPTION

FIG. 1 is a top-front-right perspective view of a coordinate input instrument according to my new design; FIG. 2 is a bottom-rear-left perspective view thereof; FIG. 3 is a right side elevational view thereof, wherein the left side elevational view is a mirror image thereof; FIG. 4 is a front elevational view thereof; FIG. 5 is a rear elevational view thereof; FIG. 6 is top plan view thereof; FIG. 7 is a bottom plan view thereof; FIG. 8 is a partial top-front-right perspective view as indicated in FIG. 1; and, FIG. 9 is a partial top plan view thereof as indicated in FIG. 6.

The dash-dot-dash lines shown in the drawings depict the boundary of the enlarged portions of the coordinate input device. The dashed line rectangles represent the general area of the enlarged views. The grayed out broken lines show portions of the coordinate input device that form no part of the claimed.

The broken lines in the figures depict portions of the coordinate input instrument that form no part of the claimed design.
